4 Claims. (Cl. 250—20)

The invention relates to a radio receiving or circuit arrangement in which a multi-grid tube is utilized for the rectification or modulation and simultaneously for the production of high-frequency oscillations, more particularly to those circuit arrangements wherein one of the grid circuits comprises an oscillatory circuit in which owing to the reactive coupling of another grid or to the presence of a negative resistance, oscillations are produced and wherein the electrodes which serve to produce oscillations are located in closer proximity to the cathode than the grid to which a variable bias is applied in order to regulate the amplification.

Such a circuit arrangement is represented in Figure 1 of the accompanying drawing. This figure represents a discharge tube T comprising a cathode K and an anode A between which a plurality of grids 1, 2, 3, 4, 5 and 6 are located. The grid 4 is connected to a circuit 7 to which the received oscillations are supplied. The connecting lead between the grid 4 and the cathode comprises furthermore a resistance 8. The voltage drop produced in said resistance serves to regulate the amplification and is preferably determined by the amplitude of the received carrier oscillations. The local oscillations are produced in a circuit 9 which is connected to the grid 1 through a grid condenser 10 with a leakage resistance 11. The grid electrode 2 which acts as an anode for producing oscillations and which hereinafter will be referred to as oscillator anode, is connected to the source of anode voltage through a retroaction coil 12 and a resistance 13 bridged by a condenser 14. The retroaction coil 12 is coupled to the inductance of the circuit 9 so that in the latter oscillations are produced. The anode A is connected to the source of anode voltage through a circuit 15 which is tuned to the intermediate frequency desired. The screen grids 3 and 5 are conductively connected to one another either inside or outside the tube and are connected to a source of anode voltage through a resistance 16 in parallel with a condenser 17. The grid 6 is conductively connected to the cathode as shown.

It has been found that when in the circuit arrangement described due to the increase of the voltage drop in the resistance 8 depending on the amplitude of the carrier oscillation received, the bias potential of the grid 4 becomes more negative, the amplitude of the local oscillations increases and furthermore the frequency thereof varies.

The invention has for its object to provide a

circuit arrangement in which the amplitude and the frequency of the local oscillations are constant.

According to the invention, this is achieved by applying a variable portion of the bias voltage for regulating the amplification to one or more of the oscillator electrodes or screen grids or to both these kinds of electrodes of the multi-grid tube.

One mode of realization of the circuit arrangement according to the invention is shown in Figure 2 in which the negative terminal of the source of anode voltage 20 is connected as by a sliding contact to an adjustable point 18 of the resistance 8 so that a portion of the variable voltage supplied to the resistance 8 is applied to the oscillator anode 2, the screen grids 3 and 5 and the anode A. It has been found that an exact adjustment of the point 18 of the resistance 8 renders it possible to obtain constancy of the frequency and of the amplitude of the local oscillations independently of the bias potential applied to the grid 4.

Having described our invention, what we claim as novel and desire to secure by Letters Patent is:

1. In a combined oscillator and detector device, the combination of an electron discharge tube having a cathode, an oscillator grid, an oscillator anode, a signal grid and a plate arranged in the order named, an input circuit including a coil shunted by a condenser and tunable to the signal frequency, a resistor having one end connected to the lower end of said coil and its other end to said cathode, the upper end of said coil being directly connected to said signal grid; a second coil shunted by a condenser and resonant to a local oscillation frequency, a direct connection between one end of said second coil and said cathode, a circuit including a series resistor connecting the other end of said second coil and said oscillator grid, a condenser shunted across said resistor, a source of positive potential, a circuit including the series connection of a third coil and a resistor connecting the positive terminal of said potential source and said oscillator anode, said third coil being inductively coupled to said second coil, a circuit connecting the negative terminal of said potential source to said cathode and a circuit connecting the positive terminal of said potential source and said plate and including a portion resonant to the intermediate frequency.

2. In a combined oscillator and detector device, an electron discharge tube having a cathode, a plate and a plurality of grids located between said plate and cathode, a circuit tuned to the hetero-

dyne frequency connected between one of said grids and cathode, a source of positive potential, a circuit connected to a second of said grids and the positive terminal of said potential source and including a feedback connection to said first circuit, a circuit connected to a third of said grids and cathode and including the series connection of a resistor and a reactance tunable to the signal frequency, and a conductive connection between 10 an intermediate point on said resistor and the negative terminal of said potential source.

3. In combination in a combined oscillator and detector, a vacuum tube having a cathode, a plate, and an oscillator grid, an oscillator grid-anode, 15 and a signal grid arranged between said cathode and plate in the order named, a circuit tuned to a local oscillation frequency connected to said oscillator grid and cathode, a source of potential, a circuit conductive to direct current connected 20 to the positive terminal of said potential source and said grid-anode and including a feedback connection to said last named circuit, an output circuit connected to said plate and the positive terminal of said potential source, a circuit connected to said signal grid and cathode and including the series connection of a fixed resistor and a reactance tunable to the signal frequency, a contact adjustable along said resistor and a direct current connection between said contact and

the negative terminal of said potential source whereby adjustment of said contact along said resistor simultaneously regulates the bias voltage of said signal grid and the voltage between said cathode and grid-anode.

4. In a combined oscillator and detector device, an electron discharge tube having a cathode, a plate and an oscillator grid, an oscillator grid-anode and a signal grid located between said cathode and plate, a circuit tuned to a local oscillation frequency connected to said oscillator grid and cathode, a source of potential, a circuit conductive to direct current connected to the positive terminal of said potential source and said grid-anode and including a feedback connection to said last named circuit, an output circuit connected to said plate and including a portion tuned to the intermediate frequency, a circuit connected to said signal grid and cathode and including a portion tunable to an incoming signal frequency, and a single adjustable control means arranged to decrease the direct current potential of said signal grid and to also decrease the direct current potential difference between said grid-anode and said cathode whereby the frequency of the locally generated oscillations remains substantially constant upon adjustment of said control means.
